PUMP

Franklin Earl Knapp, Dayton, Ohio

Application November 3, 1943, Serial No. 508,783

5 Claims. (Cl. 103—178)

This invention relates to pumps and one object of the invention is to provide a pump of the radial type which will be simple in construction and highly efficient in operation when used either with gases or with liquids.

A further object of the invention is to provide a pump of large capacity which may be operated at high speeds and will operate efficiently at all speeds.

A further object of the invention is to provide a pump of such a construction that it can be manufactured at low cost.

A further object of the invention is to provide a pump of the radial type having improved means for actuating the several pumping units in properly timed relation one to the other.

A further object of the invention is to provide such a pump in which the valve mechanisms will be easily accessible for inspection and repair.

A further object of the invention is to provide such a pump in which all operating parts of the pumping unit may be removed through the outer end of the cylinder.

A further object of the invention is to provide such a pump in which the pumping unit may be removed from the pump casing, disassembled and reassembled without the use of tools other than a wrench.

A further object of the invention is to provide such a pump in which the cylinder of each pumping unit is charged by projecting the piston into the inlet chamber of the pump casing.

Other objects of the invention may appear as the pump is described in detail.

In the accompanying drawings Fig. 1 is a top plan view of a pump embodying my invention; Fig. 2 is a front elevation of the pump with the end wall of the casing removed and partly in section; Fig. 3 is a section taken through the pump on the line 3—3 of Fig. 1 and partly in elevation; Fig. 4 is a sectional view taken centrally through one of the pumping units; Fig. 5 is a plan view of the valve supporting spider in the piston; Fig. 6 is a sectional view of that spider; Fig. 7 is a plan view of the stationary member of the outlet valve unit; and Fig. 8 is a section view taken centrally through said valve member.

In these drawings I have illustrated one embodiment of my invention and have shown the same as embodied in a pump of the radial type but it will be understood that this particular embodiment has been chosen for the purposes of illustration only and that the pump as a whole

as well as the several parts thereof may take various forms.

In the embodiment here illustrated the pump comprises a casing 10 having within the same a cylindrical chamber 11, the front side of which is closed by an end member 12 having a tapered wall which projects outwardly and is provided with an opening 13 which constitutes an inlet to the pump chamber. If desired, a screen 14 may be interposed between the inlet and the pump chamber. Mounted on the casing 10 and spaced apart circumferentially thereof are a plurality of pumping units 15, in the present instance four, each of which comprises a cylinder 16 having means whereby it may be detachably mounted on the casing and having within the same a piston 17 the inner end of which is provided with an inlet and is adapted to be projected into the chamber 11 of the casing and to be engaged therein by an actuating device. This actuating device may take various form and may be actuated in various ways. Preferably it is circular in form and is mounted in the chamber 11 for bodily movement in a path concentric with the axis of that chamber. In the particular embodiment illustrated the casing 10 is provided with an axial extension 18 having bearings 19 and 20 in which is rotatably mounted a driving shaft 21, the inner end of which extends into the chamber 11 and has rigidly secured thereto a crank arm 22 which is provided with a wrist pin 23 on which the circular actuating device is mounted. It is desirable that the outer part of the actuating device, which contacts 35 with the pistons, should be rotatable about its individual axis and the actuating device is shown as comprising a ball bearing, the inner race 24 of which is mounted on the wrist pin 23 and the outer race 25 of which is supported on the inner race by the balls 26 and has a smooth outer surface.

Each pumping unit is separately attached to the casing in such a manner that it can be readily attached to or removed from the same and, as here shown, the cylinder 16 has an inner portion 27 of reduced diameter and provided with screw threads to engage a screw threaded opening in the wall of the chamber 11, the reduced portion of the cylinder forming on the body thereof a shoulder 28 which is drawn tightly into engagement with the outer surface of the casing wall. The cylinder is preferably of uniform diameter throughout its length. The piston 17 is of elongate form so that it will have ample bearing and sealing surface in the cylinder when it has been

projected to its innermost position and it is here shown as tubular in form. The inner end of the piston, that is the end which enters the chamber 11, is provided with an end wall or head 29 having therein lateral passages 30 in open communication with the chamber 11 and leading to an inlet port 31 which in turn leads to the interior of the tubular piston which is always in open communication with the interior of the cylinder 16. The inlet port has at its inner end a valve seat 32 with which cooperates a valve member 33 arranged within the tubular portion of the piston. The valve member is provided with a stem 34 which is slidably mounted in a guideway in a spider or apertured disk 35 supported within the piston. In the construction shown the outer end portion of the piston is of slightly larger interior diameter than the inner portion, thus providing a shoulder 36 on which the apertured disk is supported and on which it is retained in a manner which will be hereinafter described. A spring 37 confined between the valve member 33 and the disk 35 retains the valve member yieldably upon its seat but is of such tension as to permit the valve to be opened by the pressure of the liquid as the piston moves inwardly and thus admit fluid to the cylinder. The inner end portion of the head 29 is tapered to provide a contact surface of relatively small area and preferably the contact portion of the head is in the form of a removable member 38 of such a character that it will have relatively small frictional contact with the surface of the actuating device. When, as in the present instance, the contact portion of the actuating device is of steel the contact member 38 of the piston is preferably of brass.

An outlet valve unit is mounted at the outer end of the cylinder and removably attached thereto and in its preferred form this unit comprises a disk-like stationary valve member 39 having a series of apertures 40 extending through the same and provided with a central guideway in which is mounted the stem 41 of the movable valve member 42, which cooperates with a valve seat 43 on the outer side of the disk and surrounding the apertures 40. On the inner side of the disk 39 the valve stem 41 is provided with a shoulder, here shown as a washer 44 mounted on the stem and retained thereon by a pin 45. A spring 46 confined between the shoulder 44 and the disk 39 yieldably retains the valve member 42 on its seat. In the arrangement shown the valve member 39 has a reduced portion 47 which extends a short distance into the outer end of the cylinder and forms on the inner portion of the disk a shoulder 48 which engages the end of the cylinder wall, a gasket 49 being interposed between the shoulder and the cylinder wall. The apertured disk 39 may be rigidly but removably secured to the cylinder 16 in any suitable manner, as by a cap 50 screw threaded onto the cylinder and provided with a shoulder 51 to engage the outer face of the disk 39 and clamp the latter tightly against the end of the cylinder. On the outer side of the disk 39 the cap is provided with a chamber 52 in which the valve member 42 moves and into which the fluid from the cylinder is discharged through the apertures or ports 40. The cap is provided with an outlet which is here shown as a threaded aperture 53 formed in the end wall of the cap and adapted to receive the threaded end of a suitable conduit.

Confined between the stationary member or disk 39 of the outlet valve and the spider or disk 75

35, which supports the inlet valve, is a spring 54 which serves to retain the disk 35 on the shoulder 36 and to move the piston inwardly and project the inner end thereof into the chamber of the casing and retain the same in contact at the periphery of the actuating device as the latter revolves about the axis of the drive shaft. Upon the inward movement of the piston by the spring 54 the outlet valve closes and the movement of the piston tends to create a vacuum within the cylinder, and the valve 33 opens under the pressure of the fluid in the chamber, thus permitting the fluid to flow into the cylinder and fill both the cylinder and the tubular portion of the piston. As the piston is moved outwardly by the actuating device the inlet valve closes and the pressure exerted on the fluid within the cylinder by the piston opens the outlet valve and discharges the fluid through the chamber 52 and outlet 53. Due to its relatively great length the piston has a large sealing contact with the cylinder which will prevent the passage of gaseous fluids, as well as liquids, between the cylinder and the piston, thus enabling the pump to compress gases to a high pressure. The pump can be used for pumping either gases or liquids without change except that with heavy liquids it will usually be preferable to use a heavier spring 54 than is used in pumping gases. Due to its tubular character the piston does not reduce the internal capacity of the cylinder but actually increases that capacity when the piston is in its innermost position. The construction is such that the actuating device can be rotated at high speed and the several pistons reciprocated at a correspondingly high speed, thus imparting to the pump as a whole a large capacity and the pump will operate at high efficiency at all speeds.

It will be apparent from the foregoing description that each pumping unit is complete in itself and may be attached to or detached from the pump casing at will and that the valves and other operating parts are readily accessible for inspection or repair. By removing the cap 50 all the parts within the piston may be withdrawn through the outer end of the cylinder and may then be quickly and easily reassembled in the cylinder. The pumping unit is also of such a character that it can be produced at a very low cost. Practically all the parts can be formed on a screw machine and the inlet passages 30 consist of two intersecting bores each of which extends entirely through the piston head.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent is:

1. A pumping unit for a pump mechanism comprising a cylinder having means whereby the inner end thereof may be mounted on and secured to a pump casing and having uniform internal diameter throughout its length, a tubular piston mounted in said cylinder and having a uniform external diameter throughout its length, the piston having an inlet port adjacent one end thereof, a valve in said piston to control the flow of fluid through said inlet port, a disk extending across the outer end of said cylinder and having a guideway and a plurality of openings therethrough, a valve member supported in said guideway and extending across the outer ends

of said openings, a cap detachably mounted on said cylinder, engaging said disk to secure the latter to said cylinder and having an outlet, and a spring confined between said disk and said piston to project the inner end of said piston beyond the inner end of said cylinder.

2. A pumping unit for a pump mechanism comprising a cylinder having its inner end portion provided with an external screw thread to enable it to be removably mounted in the wall of a pump casing, a tubular piston mounted in said cylinder and having an end wall provided with lateral openings and an inlet port connecting said openings with the interior of said piston, said port having a valve seat, said piston also having an internal shoulder spaced from said end wall, an apertured disk supported on said shoulder and having a central guideway, a valve member having a stem slidably mounted in said guideway, a spring confined between said disk and said valve member to yieldingly retain the latter on said valve seat, a second apertured disk at the outer end of said cylinder having a central guideway, a valve member on the outer side of said second disk having a stem slidably mounted in the guideway thereof, said stem having a shoulder on the inner side of said second disk, a spring confined between said shoulder and said second disk to yieldably retain the last mentioned valve member in engagement with said second disk, a cap screw threaded on said cylinder, having an internal shoulder engaging said second disk and also having a chamber on the outer side of said second disk and provided with an outlet, and a spring confined between said disks to retain the first mentioned disk on the shoulder in said piston and to project the end portion of said piston beyond the inner end of said cylinder.

3. A pumping unit for a pump mechanism of the type including a casing having an inlet, and an actuating device within said casing, said pumping unit comprising a cylinder having means whereby it may be removably mounted on said casing in communication with the interior thereof, a tubular piston mounted in the inner portion of said cylinder and removable through the outer end thereof, said piston having at one end a part adapted to extend into said casing and to have sliding contact with the actuating device within the latter and having adjacent said end an inlet port to connect the interior of said piston with the interior of said casing, an inlet valve unit removably supported in said piston and comprising a stationary member and a movable member to control the flow of fluid through said inlet port, an outlet valve unit supported by the outer end of said cylinder and comprising a stationary member removably supported on said cylinder and a movable member carried by said stationary member, a closure removably secured to said cylinder and engaging said stationary member of said outlet valve unit to secure the latter to said cylinder, said closure having a chamber in which the movable member of said outlet valve unit operates and having an outlet port, and a spring confined between said stationary members of the two valve units to hold the stationary member of said inlet valve unit against movement and to project the inlet end of said piston beyond the inner end of said cylinder, whereby said pumping unit may be removed from said casing and then completely disassembled by removing the closure.

4. A pumping unit for a pump mechanism of the type including a casing having an inlet, and an actuating device within said casing, said pumping unit comprising a cylinder having means whereby it may be removably mounted on said casing in communication with the interior thereof, a tubular piston mounted in the inner portion of said cylinder and removable through the outer end thereof, said piston having at one end a part adapted to extend into said casing and to have sliding contact with the actuating device within the latter and having adjacent said end an inlet port to connect the interior of said piston with the interior of said casing, an inlet valve unit removably supported in said piston and comprising a stationary member and a movable member to control the flow of fluid through said inlet port, an outlet valve unit comprising a disk seated in the outer end of said cylinder and provided with a central guideway and a plurality of apertures arranged about said guideway, a movable guide member arranged on the outer side of said disk to control the flow of fluid through said apertures and having a stem slidably mounted in said guideway, said stem having a shoulder on the inner side of said disk, and a spring confined between said shoulder and said disk to move said movable member into aperture closing relation to said disk, a cap removably supported on said cylinder and engaging said disk to secure the latter on said cylinder and having a chamber in which said movable outlet member operates and an outlet port for said chamber, a spring confined between said disk and the stationary member of said inlet valve unit to hold the latter against movement and to project the inner end of said piston beyond the inner end of said cylinder, whereby said pumping unit may be removed from said casing and then completely disassembled by removing said cap.
5. A pumping unit for a pump mechanism of the type including a casing having an inlet chamber and an actuating device in said chamber, said unit comprising a cylinder connected with said casing and the inner end of which is adapted to communicate with said chamber, a tubular piston in said cylinder and removable through the outer end thereof, said piston having a closed inner end projecting into said chamber and having sliding contact with said actuating device, said piston also having an inlet port to connect the same with said chamber, a pressure controlled valve to control the flow of fluid through said inlet port and removable through that end of said piston opposite said port, pressure controlled means for controlling the flow of fluid from said cylinder including a movable outlet valve member, and a supporting and guiding member for said valve member removably mounted on the outer end of said cylinder and having a fluid passage, and a closure removably mounted on said cylinder, engaging said supporting and guiding member to secure the latter to said cylinder and having an outlet port communicating with the passage in said supporting and guiding member, and spring means urging the inner end of said piston into said chamber and removable through the outer end of said chamber, whereby said pumping unit may be entirely disassembled for removing said closure.
